UNITED STATES PATENT OFFICE.

CONRAD REHBEIN, OF DETROIT, MICHIGAN, ASSIGNOR TO HAYES MANUFACTURING CO.,
OF DETROIT, MICHIGAN, A CORPORATION OF MICHIGAN.

EDGE-BENDING MACHINE.

1,272,999.

Specification of Letters Patent. Patented July 16, 1918.

Application filed June 25, 1917. Serial No. 176,708.

To all whom it may concern:

Be it known that I, CONRAD REHBEIN, a citizen of the United States, residing at Detroit, county of Wayne, State of Michigan, 5 have invented a certain new and useful Improvement in Edge-Bending Machines, and declare the following to be a full, clear, and exact description of the same, such as will enable others skilled in the art to which it 10 pertains to make and use the same, reference being had to the accompanying drawings, which form a part of this specification.

This invention relates to metal bending machinery and especially what is known as 15 an edge-bender; that is to say, a machine which is designed to bend sheet metal in the plane of the metal, which of course, is ordinarily very difficult as it has its maximum strength in this direction.

20 In the drawings,—

Figure 1 is a side elevation of the machine with some of the parts broken away.

Fig. 2 is a plan view.

Fig. 3 is an end elevation.

25 Fig. 4 is a section of a part of one of the rolls and the forming block as used.

Fig. 5 is a sectional detail of the rolls.

30 *a* designates the frame; *b* the speed reduction gears; *d* the drive shaft; *e* the driven shaft provided with a beveled pinion *f* that meshes with the oppositely facing beveled pinions *g*, *h* loosely running on the drive shaft *d*. The jaw clutch *i* serves to connect either one of these loose pinions *g* 35 and *h* to the drive shaft, and therefore, acts as a power reversing clutch which is controlled from a handy position near the top of the machine by reason of the bent lever *j* and the link *k*.

40 It will be noted that the driven shaft *e* is journaled vertically in the frame and carries at its top a roller *l* which has a pair of annular grooves *m* in its periphery adapted to receive the metal strip or work *n*. This 45 work is what is known as a stiffening for an automobile fender. These strips are cut out straight from the stock and then bent edge-wise to the desired contour of the fender, which may be a double reversed curve if a 50 front fender, and an almost semi-circular curve if a rear fender. However, in bending for a reverse curve, two forces are used, one after the other, as the strips have to be laid in the forming block with the beads

and wires on the outside instead of on the 55 inside as shown in Fig. 4. The forming roll has also to be changed. Cutting these strips from straight stock is, of course, a great saving in material from the practice of cutting them out in a curved form. 60

The forming block *o* (when used for rear fenders) may be of the curvature desired for the finished strip and, of course, may be varied within quite broad limits. In cross section it may be U shape (Fig. 4). The 65 uprights of the U each carry one stiffening strip. The folded-over edge of the stiffening strip which is intended to be rolled in with the main web of the fender, turns over to the outside of the upright of the U. The 70 bead of the strip which carries the stiffening wire already rolled in, rests at the bottom of the U and a small protuberance *q* forms a seat on either side of the protuberance for each of these beads. Or when bending in 75 the opposite direction the U-like pushing should be on the roll and the complementary pushing on the form. This can be accomplished by changing the roll and changing 80 the form.

It will be seen that when the forming block *o* is brought into engagement with the form roll *l* that the forming block and the form roll each serve to completely incase 85 the cross sectional portion of the stiffening strip in contact with the two members so that when the bending strain is upon the stiffening strip, no distortion of the stock can occur. In Fig. 2 it will be seen that the forward end of the stiffening strip is 90 clamped to the forming block by the clamp *r*. The forward end of the forming block may be put between the form roll *l* and the guiding roll *s*, which is a roll having a plain 95 periphery and a pair of collars *t*, *t*, for engaging about the forming block. When the forming block with the stiffening strip clamped in place is put between these two rolls, the rolls are drawn together by turning the lever *u*, which is journaled in the 100 journals *v*, *v*, of the frame *a*. This lever is connected with a rock shaft *y* that in turn connects rigidly with the lever arm *z*. At the end of this lever arm *z* a link 1 is pivoted which is connected to the bifurcated 105 end of the sliding rod 2 that connects with the slide 3 through the coil spring 4. The slide 3 journals the plain roll *s*. In the

standard 5 is journaled the double-grooved roll 7. Now obviously by throwing the lever shown in Fig. 1 away from the viewer, the slide 3 can be made to move away from the standard 5 so as to separate the rolls, and when it has moved away far enough to bring the pivot 10 on the lever 1 to the other side of the straight line drawn between the points on which the lever and link swing, 10 the spring 4 having passed the dead center thrust line, will tend to keep the levers and the link in this position.

The stiffening strips are clamped on to the forward end of the forming block as shown 15 in Fig. 2, and will take the position when viewed in cross section as shown in Fig. 4. Consequently when the two rolls *s* and *l* are brought together by throwing the toggle arms of the control apparatus, the spring will 20 securely hold the rolls and form together and the metal is completely socketed in the restraining walls of the form and the forming roll so that it is obliged to follow the contour of the form as the same is pulled 25 through the rolls by the driving of the roll *l*, which as already shown, is connected up with the power by a large speed reduction gearing. The other roll is an idler to carry the form through the rolls without friction. 30 By using the idler roll differential speed of the rolls can be secured without differential gearing, which is quite an advantage and

differential speed is necessary because of the curvature of the form.

What I claim is:

1. In an edge bending machine for bending stiffening strips for automobile fenders and similar strips, the combination of a driving roll, an idler roll, means for drawing the said roll toward and away from said driving roll including a spring for allowing relative movement after the rolls are in a set position and to furnish pressure for frictional driving of the roll and devices passing between the rolls, and a forming block 45 having a longitudinal contour curved to the bend desired for the strip, the peripheries of the said block and one of the rolls being shaped to completely ensheath and restrain all the sides of one or more strips, said idler roll and forming block being driven solely by friction.

2. In an edge bending machine, the combination of a driven roll, an idler roll opposite the driven roll and both provided with 55 grooves having uninterrupted surfaces, a longitudinally arcuate forming block having one or more grooves in one face and propelled through the rollers solely by friction, and means for yieldingly pressing the 60 rollers and forming block together.

In testimony whereof I sign this specification.

CONRAD REHBEIN.
